AUTOMOBILE SEAT COVER OR SIMILAR ARTICLE

Arlene K. Bucher, 336 S. 8th St.,
Lebanon, Pa. 17042

Filed Aug. 21, 1968, Ser. No. 13,225

Term of patent 14 years

Int. Cl. D6—01

U.S. Cl. D15—8

FIG. 1 is a front perspective view of an automobile seat cover or similar article embodying my design;

FIG. 2 is a top plan view of the seat cover shown in FIG. 1;

FIG. 3 is a front elevational view thereof;

FIG. 4 is a rear elevational view thereof; and

FIG. 5 is a side elevational view thereof, the opposite side being a mirror image thereof.

I claim:

The ornamental design for an automobile seat cover or similar article, as shown and described.
